LEWIS FERRY MOODY, OF PHILADELPHIA, PENNSYLVANIA.

PUMP AND METHOD OF REGULATING THE SAME.

Original application filed July 3, 1919, Serial No. 308,607. Patent No. 1,460,428, dated July 3, 1923.
 Divided and this application filed January 2, 1923. Serial No. 610,096.

To all whom it may concern.:

Be it known that I, LEWIS FERRY Moody, a citizen of the United States, residing at Philadelphia, in the county of Philadelphia 5 and State of Pennsylvania, have invented certain new and useful Improvements in Pumps and Methods of Regulating the Same, of which the following is a specification.

10 This invention relates to hydraulic pumps and methods for regulating the same and particularly to such pumps having a rotary impeller. The object of the invention is to provide a pump and method of control 15 therefor whereby the amount of water pumped may be regulated within wide limits while maintaining highly efficient flow conditions at all adjustments.

A common method of regulating pumps is 20 by means of a gate valve or some similar valve in the discharge pipe for throttling the flow after the water has left the pump. Such a valve usually reduces the flow by interposing a loss of head and thus controls the 25 pump mainly by reducing its efficiency. In the pump of this invention regulating means is provided in the pump inlet leaving the outlet free from obstruction and supplying the impeller with a widely variable quantity 30 of water in such manner that efficient conditions of flow at both the inlet and outlet are maintained at all degrees of opening.

Other objects and advantages of the invention will appear in the following description 35 taken in connection with the accompanying drawing in which a vertical section of a pump is shown illustrating one embodiment of the invention.

In the pump shown in the drawing power 40 is supplied from the coupling 5 and shaft 6 to rotate impeller blades 7 which are of the axial screw type and draw water from the inlet casing 8 and drive it through the outlet casing 9. The inlet casing 8 has an 45 axial flow inlet passage narrowing the flow and directing it axially and tangentially through the gate space 11 to the transition space 12 where it passes to the impeller blades 7. In the outlet casing 9 the flow 50 from the impeller is turned outward away from the axis and gradually broadened in section. In passing through the pump the flow in the inlet is increased in velocity so that it has its pressure head transformed

largely into velocity head at the impeller 55 blades 7, while in the outlet 9 the velocity of flow is gradually reduced retransforming the velocity head into pressure head much higher in degree, of course, than that at the inlet. The inlet casing 8 is bolted to the 60 outlet casing as at 15.

The water enters this pump in an axial direction at the inlet 8, is given an initial whirling motion by a series of fixed vanes 16 and is discharged from these vanes into 65 the wicket gates 32 which further continue the guidance and discharge the water with an increased amount of whirl in the space 12 between the wicket gates and the impeller 7. It is essential that a sufficient space be 70 provided between the entrance vanes and impeller to allow the water to come together in a continuous revolving mass of substantially uniform velocity around the circumference before it enters the impeller. The 75 guide vanes are of the axial flow type with axes radiating from the axis of the pump and their axes are shown in the same plane although they might be equally well contained in a conical surface having its apex 80 in the pump axis. In the structure shown the inner vane spindles 35 are journaled in a ring 36 carried by the central guiding cone 37 which in turn is supported by the fixed guide vanes 16 of inlet casing 8. The outer 85 spindles 38 of vanes 32 are continued through bearings formed between inlet casing 8 and outlet casing 9 and are provided with levers 40, an adjusting ring 42 and intermediate links 41, the end pins of which 90 are inclined so that all their axes intersect the pump axis at the same point as the intersection of the spindle axes. Therefore, in all positions of the wicket gates the pins 95 mounted on the levers will continue to intersect the same fixed point and a correct fit at all the pivots may be maintained.

The cone 37, ring 36 and the hub 43 of the impeller merge smoothly in contour with each other and with the central walls of the outlet casing 9. The outer walls of the inlet and outlet casings are also formed to merge with each other and gradually decrease the section and increase the velocity of the inflow to the impeller and then 100 conversely increase the section and decrease the velocity of the outflow therefrom to retransform the velocity head into pressure head at 105

the outlet. The guide vanes 32 are formed with their outer edges shaped to fit the inlet casing walls 30 when they are closed; and with their inner edges shaped to fit 5 the ring 36 which is made spherical in the portion coming in contact with the vanes. The adjusting ring 42 will be moved by an extension arm and draw rod connected to a piston or hand wheel as desired and all the 10 vanes 32 are moved in exactly similar manner and are therefore given equal relative angular positions at all openings.

The guide vanes 32 may be arranged both to close to smaller amounts of opening than 15 their normal position and to open to positions for greater discharge than normal and their number and length are preferably such that they may be closed to shut off the supply to the pump altogether.

20 The water is brought to the wicket gates 32 in the axial passage of the inlet casing and receives an initial whirl from the fixed guide vanes 16 and an additional whirling motion from the gates 32; the water thus 25 enters the impeller in a continuous revolving stream of substantially uniform velocity around the circumference.

By this means the flow through the pump 30 is regulated without loss of head and with- out substantial variation in efficiency at the different adjustments; for the only difference in conditions of efficiency introduced by this adjustment is the slightly variant angle at which the lines of flow of the axial stream 35 enter the impeller due to variations of the adjusted angles of the movable vanes.

Another advantage of the structure of this 40 invention in regulating the flow in the inlet is that it leaves the outlet clear of obstruc- 45 tion and free to be designed to secure the most efficient transformation of the velocity head at the impeller into pressure head at the outlet. Adjustable guide vanes in this outlet passage would break up the continu- 50 ity of the diffusion and introduce wasteful disturbances; for the passages through the guide vanes are too short in comparison with their width to be effective as diffusers and, if very long vanes are used, the heavy 55 mechanical load required to adjust them makes them impractical and the additional friction due to the large aggregate amount of surface on the vanes would introduce serious hydraulic losses. These objections are 60 not involved when the vanes are placed on the entrance side of the impeller since at this point in the pump the water is being accelerated and the passages between the vanes contract in area instead of expanding.

65 The vanes may be formed to give highly efficient flow conditions at all angles of opening, acting simply to vary the amount of the flow and imparting a slightly variant angle of impact at the impeller blades.

65 The pump of this invention is simple and

compact in form receiving the flow axially and discharging it in any desired direction by means of a discharge casing such as that shown at 9. In the specific embodiment shown, the impeller 7 is overhung at 70 the end of the shaft 6 which runs in bearings 19, 20 and 21 and tubular housing 22 integral with the outlet casing 9. The impeller and shaft may be removed by lifting off 75 the upper half of the outlet casing 9. In this pump the regulating means is placed relatively near the impeller so that the increased velocity caused by the movable vanes both in normal position and when partially 80 closed enters the impeller without the loss of head which would be caused if this velocity were maintained through a considerable length of path. The direction of flow as projected in the plane of the figure becomes 85 axial in the vane space 11 slightly in advance of the impeller 7 so that when it reaches the impeller it is somewhat divergent with respect to the impeller axis and this divergence continues through the impeller. The spiral discharge conduit 9 receives the 90 flow from the annular space between the outer diverging surface and the inner expanding conical surface and this spiral discharge develops in a direction increasingly 95 divergent from the axis.

This application is a division of my co-pending application Serial No. 308,607, filed July 3, 1919, for pump and method of regulating the same, now Patent No. 1,460,428, July 3, 1923, and is a continuation in part 100 of my application Serial No. 233,210, filed May 8, 1918, now Patent No. 1,321,538, November 11, 1919.

I claim:

1. In a pump the combination with a rotary impeller, of an inlet directing the inflow to said impeller with the meridian components of the velocity substantially parallel to the axis, and movable guide vanes regulating the flow through said inlet, all of 110 said guide vanes being linked to a single operating ring to be similarly adjusted thereby, said movable guide vanes turning on axes intersecting at the axis of said operating ring.

2. In a rotary hydraulic pump, the combination of an impeller, an axially directed inlet passage receiving the flow axially and adapted to deliver the water to said impeller under a considerable head and having adjustable means in said axially directed inlet passage to convert the energy of that head into a high velocity of whirl of the entering water around the axis of the impeller, and means to deliver the water therefrom with a whirl in the same direction and to convert that whirl into static head on the outflow side of the pump.

3. In a rotary hydraulic pump, the combination of an impeller, a casing around the 130

same having an axial inflow conduit receiving and delivering the flow axially and adjustable means within said axial inflow conduit to create a whirl therein, and a spiral conduit to receive the water from the impeller, said impeller casing opening into said spiral conduit by a diverging annular passage.

4. In a rotary hydraulic pump, the combination of a high speed impeller adapted to pass a stream of water therethrough of comparatively small cross section and at high velocity, an axial inlet passage receiving the flow axially and adapted to deliver the supply water to the impeller under considerable head and to utilize the same to move the water into the impeller at a proper high speed, adjustable means in said axial inlet passage for imparting a whirl to the flow, and means on the outflow side of the pump to receive the water from the impeller with high velocity energy and to convert the same into static head.

5. A rotary hydraulic pump having in combination a high speed impeller, an axial inflow conduit, and an outflow conduit, said conduits and the impeller being disposed so that the course of the water flowing through the pump shall be in a continuously advancing helical path first converging to its smallest cross section in advance of the impeller and then diverging therefrom, the cross section in advance of the impeller being such as to give a high velocity there-through compared with the velocity corresponding to the net head of the pump.

6. A rotary hydraulic pump for operating at a moderate net head having in combination a high speed impeller, an axial inflow conduit, and an outflow conduit, said conduits and the impeller being disposed so that the course of the water flowing through the pump shall be in a continuously advancing helical path first converging to its smallest cross section in advance of the impeller and then diverging therefrom, said conduits being so formed that the cross sections of the stream elements across the lines of flow are less in accordance with nearness to the impeller.

7. A rotary hydraulic pump having in combination an impeller of substantially axial flow type, an admission chamber formed to deliver water to the impeller with a large whirl component of velocity and comprising an axial inlet passage and adjustable vanes in said passage, an annular discharge space bounded by surfaces of revolution co-axial with the impeller to receive the discharge therefrom and a spiral conduit to receive the discharge from the annular discharge space and formed to receive the water entering it in a direction diagonal to the impeller axis.

8. In a rotary hydraulic pump the com-

bination of an impeller, an axial inlet passage to deliver the water thereto under a considerable head and having adjustable vanes to convert the energy of that head into a high velocity of whirl of the entering water around the axis of the impeller, and a spiral conduit of expanding cross section to receive the water from the impeller with a whirl in the same direction and to reduce its velocity so as to convert such whirl into static head on the outflow side of the pump.

9. A rotary hydraulic pump having in combination a high speed impeller, a driving shaft therefor, an axial inflow conduit around the axis of said shaft approaching convergently to the impeller, adjustable vanes in said inflow conduit, and an outflow conduit around said shaft receding divergently from the impeller.

10. A rotary hydraulic pump having in combination an impeller of high speed compared with the velocity corresponding to the head, a converging axial inflow conduit having adjustable means within it adapted for giving the water a variable whirl velocity as it goes to the impeller, and a diverging spiral outflow conduit adapted for reconverting the high whirl velocity of the water as it leaves the impeller and making it available as static head.

11. In a pump the combination with a rotary impeller, of means directing the inflow to said impeller axially and increasing its velocity, and means for regulating the flow through said pump comprising means for varying the angle of whirl of said axial inflow.

12. In a pump the combination with a rotary impeller, of means directing the inflow to said impeller axially and increasing its velocity, and means for regulating the flow through said pump comprising means for simultaneously varying the velocity and angle of whirl of said axial inflow.

13. In a pump the combination with a rotary impeller, of means directing the inflow to said impeller axially and increasing its velocity, and means for regulating the flow through said pump comprising means for imparting an initial whirl to said inflow and subsequently increasing this whirl in variable manner.

14. In a pump the combination with a rotary impeller, of means directing the inflow to said impeller axially and simultaneously increasing its velocity, and means for regulating the flow through said pump comprising means for variably changing the angle of whirl of said axial inflow in advance of the impeller to regulate the flow through the pump.

15. In a rotary hydraulic pump the combination with an impeller, of an axial inlet passage having means for imparting a whirl to the flow, and means in said axial inlet

- passage for varying the angle of whirl to regulate the flow through the pump.
16. In a pump the combination with an impeller, of an axial inlet casing imparting a whirl to the inflow and increasing its velocity as it approaches the impeller, and means in said axial inlet casing for varying the angle of whirl of the inflow to regulate the pump. 60
- 10 17. A rotary hydraulic pump having in combination an impeller, an axial inflow conduit, and an outflow conduit, said conduits and the impeller being disposed so that the course of the water flowing through the pump shall be in a continuously advancing helical path first converging to its smallest cross section in advance of the impeller and then diverging therefrom, the inflow conduit having means to impart a variable angle of 70 whirl to the flow so as to regulate the flow to the pump. 65
- 15 18. A rotary hydraulic pump having in combination an impeller, an axial inflow conduit, and an outflow conduit, said conduits and the impeller being disposed so that the course of the water flowing through the pump shall be in a continuously advancing helical path first converging to its smallest cross section in advance of the impeller and then diverging therefrom, the inflow conduit having axially directed wicket gates to impart a variable angle of whirl to the flow so as to regulate the flow to the pump. 80
- 20 19. In a rotary hydraulic pump the combination with an axially directed inflow conduit having guide vanes adapted to impart a whirl to the inflow, of adjustable guiding means in said axially directed conduit adapted to vary said initial whirl and 90 deliver the whirling flow to an impeller of the axial flow type. 95
- 25 20. In a pump the combination with a rotary impeller, of an axial inlet receiving and directing the flow axially to said impeller, and movable guide vanes regulating the flow to said inlet, all of said guide vanes being 100 linked to a single operating ring to be similarly adjusted thereby, said movable guide vanes turning on axes at an angle to the axis of said operating ring. 105
- 30 21. In a hydraulic pump the combination with an axial flow impeller, of guiding means forming a converging inlet space in advance thereof adapted to receive and 110 guide the flow in an axial direction while increasing its velocity, inclined guide vanes in said inlet space adapted to impart a whirl
- to the flow, and adjustable guide vanes for variably regulating said whirl. 115
22. In a pump the combination with an impeller of an axial inlet conduit having guide vanes adapted to impart a whirl to the flow and a series of guide vanes arranged in the path of said inflow and adapted to increase the whirl. 120
23. In a pump the combination with an impeller of an axial inlet conduit having guide vanes adapted to impart a whirl to the flow and a series of adjustable guide vanes arranged in the path of said inflow and adapted to variably increase the whirl. 125
24. In a rotary hydraulic machine the combination with a runner of substantially axial flow type, of a series of guide vanes in advance of said runner, said guide vanes being adjustable by rotation about axes which intersect in a common point on the runner axis, levers and links connecting said vanes to a common operating ring, the connections of said links and levers turning about axes which intersect the turbine axis at the same point as the axes of rotation of said guide vanes. 130
25. In a rotary hydraulic machine the combination with a runner of substantially axial flow type, of a series of guide vanes in advance of said runner and having axes inclined to the runner axis, said guide vanes being adjustable by rotation about said inclined axes which intersect in a common point on the runner axis, levers and links connecting said vanes to a common operating ring, the connections of said links and levers turning about axes which intersect the turbine axis at the same point as the axes of rotation of said guide vanes. 135
26. In a rotary hydraulic machine the combination with a rotary runner of an inlet directing the inflow axially to said runner, and movable guide vanes in advance of said runner regulating the flow through said inlet, said guide vanes having axes inclined to the runner axis and being adjustable by rotation about said inclined axes which intersect in a common point in the runner axis, said movable guide vanes and said runner being spaced apart to leave an intermediate transition space to allow the water to come together in a continuously revolving mass of substantially uniform velocity around the circumference before it enters the runner. 140

LEWIS FERRY MOODY.
